UNITED STATES PATENT OFFICE.

REGINALD W. BIRD, OF BOSTON, MASSACHUSETTS.

PAINT-SPRAYING APPARATUS.

SPECIFICATION forming part of Letters Patent No. 728,489, dated May 19, 1903.

Application filed March 5, 1901. Serial No. 49,704. (No model.)

To all whom it may concern:

Be it known that I, REGINALD W. BIRD, of Boston, in the county of Suffolk and State of Massachusetts, have invented certain new and 5 useful Improvements in Paint-Spraying Apparatus, of which the following is a specification.

This invention relates to an apparatus for spraying paint, calcimine, or other preparation upon walls or ceilings; and its object is to provide a device which shall be readily portable or capable of being easily moved to different localities or positions on a floor, but having provisions whereby the weight of an 15 operator may be utilized to anchor the apparatus to the floor during the operation or manipulation thereof.

The invention has for its further object to provide means for effectively distributing or 20 spraying the paint or other preparation upon the surface to be treated.

Of the accompanying drawings, forming a part of this specification, Figure 1 represents a side elevation illustrating my device and 25 the manner of its operation. Fig. 2 represents a plan view of the apparatus. Fig. 3 represents a side elevation with a portion of the operator's platform broken away. Fig. 4 represents a rear elevation, partly in section 30 and with the operator's platform removed. Fig. 5 represents a side elevation showing the operator's platform and its manner of attachment to the pump-platform. Fig. 6 represents a perspective view showing the means 35 for connecting the platforms. Fig. 7 represents a detail section of the strainer covering the outlet from the paint-supply tank. Fig. 8 represents a longitudinal sectional view of the spraying-nozzle. Fig. 9 represents a section 40 on the line 9.9 of Fig. 8.

The same reference characters indicate the same parts in all of the figures.

In the drawings, 1 represents a platform, which I herein term the "pump-platform," 45 on which are mounted a supply-tank 2, adapted to contain the paint or other preparation to be sprayed, and a pump 3, which is here shown as a double force-pump, but which may be of any desired pattern, such pump 50 having a long operating lever or handle 4, a suction-pipe 5, connecting it with the supply-tank 2, a flexible discharge pipe or hose 6,

and an air-chamber 7, provided with a pressure-gage 8. The apparatus is designed to be operated by two people, one of whom operates the pump while the other handles the discharge-hose 6 and directs the spray which is discharged from the nozzle 9 at the outer end thereof.

The pump-platform 1 and the parts mounted thereon are of considerable weight, and in order to render the platform capable of being moved about upon a floor I provide it with roller casters or supports 10 at the four corners of the platform.

If a person standing upon the floor were to attempt to operate the pump 3, difficulty would be experienced in doing so because of the lack of stability of the platform, due to the movements of the platform permitted by the casters 10. It is accordingly desirable to pro-

vide means for securing or anchoring the platform to the floor during the period of its operation, such means being preferably constructed so as to be rendered quickly operative or inoperative. In the drawings I show novel means whereby the weight of the operator is caused to secure or anchor the pump-platform to the floor during the period of its operation, my invention, however, not being limited to the exact devices or means herein shown.

11 indicates an operator's platform, which forms a lateral continuation or extension of the pump-platform 1, but is detachably secured thereto and supported thereon at one end by a device which is shown clearly in Fig. 6 as consisting of a bar secured to the front edge of the platform 11 and having

projecting ends 12 12, which constitute locking members, and two upwardly-projecting hooks 13 13, secured to the rear edge of the pump-platform 1 and adapted to receive the projecting bar ends 12 12, the attachment and detachment being performed by a vertical movement of the front end of platform 11.

At the outer end of the operator's platform 11 is a rigid or non-yielding leg or support 14, which rests upon the floor when the platform 11 is operatively positioned. Fig. 1 shows the manner of operating the pumping part of

the apparatus. The upper end of the pump-operating handle 4 is arranged to swing partly over the platform 11, so that an operator standing on the platform can manipulate said

pump-handle. The weight of the operator standing on platform 11 causes a heavy pressure or frictional contact between the non-rolling support 14 and the floor, which serves 5 to anchor pump-platform 1 and prevent it from moving about while the pump is being operated. When the operator's platform 11 is relieved of the person's weight, the apparatus may then be shifted about the floor without removing the platform 11, though this operation is rendered easier and the device is made more compact if said platform 11 be removed while the device is being shifted.

The inlet end of the suction-pipe 5 within 15 the supply-tank 2 is equipped with a flaring cap or end piece 15, provided with a perforated strainer 16. Said suction-pipe also has a cock or valve 17, whereby the tank may be shut off from the pump whenever desired.

20 At the outer end of the hose 6 is a section of rigid piping 18, which the operator grasps in directing the spraying-nozzle, said section having at its inner end a valve 19 and at its outer end the spraying-nozzle 9. The construction of the latter is shown in detail in 25 Figs. 8 and 9. Its casing includes an inner chamber 20, having an inlet branch 21, into which the end of pipe-section 18 is screwed, and an outer chamber 22. The outer and inner chambers are separated by a partition 23, having a series or group of perforations 24 24, here shown as three in number, and the outer wall of said chamber is provided with a single discharge-aperture 25, located 30 opposite the middle of the group of apertures 24 24. By this arrangement the paint is distributed in a spreading stream or spray. At the opposite end of the casing from the perforated partition 23 is a clean-cut aperture 35 26, normally closed by a screw-plug 27, which may be removed to give access to the interior of the nozzle-casing and permit the latter to be cleaned out without requiring the removal of the whole nozzle from the pipe-section 18.

40 45 By the use of my improved apparatus the spraying of paint or other liquid may be carried on with great facility. The containing vessel or reservoir 2 is open at the top, so that the paint or other preparation may be 50 stirred from time to time to prevent the settling of its heavier ingredients and so that it may be easily refilled. If at any time it should be desired to disconnect the pump from the tank to clean the pump or for any 55 other purpose, this may be effected after first turning off the valve 17 by disconnecting a coupling or union 28, located in the suction-pipe 5 between the pump 3 and valve 17, and

then, if necessary, shifting the tank 2 or removing it from the platform. 60

I claim—

1. A spraying apparatus comprising a pump having operating means and rolling supporting means for engaging the floor, and an operator's foot-platform slightly elevated above 65 the floor-level and laterally extended from the pump, said foot-platform having a clear space above it to permit an operator to stand thereon and having rigid floor-engaging anchoring means.

2. A spraying apparatus comprising a pump having operating means and rolling supporting means for engaging the floor, and an operator's foot-platform having a clear space above it to permit an operator to stand thereon and slightly elevated above the floor-level and laterally extended from the pump, said 75 foot-platform having a rigid non-rolling support.

3. A spraying apparatus comprising a pump 80 having operating means and rolling supporting means for engaging the floor, and an operator's foot-platform slightly elevated above the floor-level, said foot-platform having a clear space above it to permit an operator to 85 stand thereon and being detachably secured to and laterally extended from the pump, and having a non-rolling support.

4. A paint-spraying nozzle comprising a short casing having a screw-plug at each end 90 in axial alignment, and an inlet branch 21 communicating with the side of the casing between the two plugs and having its outer end extending at an acute angle to receive a combined supply-pipe and handle, said acute 95 angle being relative to a line passing through the two plugs, the forward screw-plug having a discharge-aperture 25 and provided with a partition or diaphragm 23 having perforations out of alignment with the aperture 25. 100

5. A spraying apparatus comprising a base and a pump thereon having operating means and rolling supporting means for engaging the floor, and an operator's foot-platform movably connected with said base and laterally extended therefrom and having a clear space above it to permit an operator to stand thereon and having rigid floor-engaging means. 105

In testimony whereof I have affixed my signature in presence of two witnesses.

REGINALD W. BIRD.
